Attorney

UNITED STATES PATENT OFFICE.

AUGUSTUS S. BUNKER, OF LAWRENCE, MASSACHUSETTS.

ELECTRIC BELL-PULL.

SPECIFICATION forming part of Letters Patent No. 293,626, dated February 19, 1884.

Application filed November 26, 1883. (No model.)

To all whom it may concern:

Be it known that I, AUGUSTUS S. BUNKER, a citizen of the United States, residing at Lawrence, in the county of Essex and State of Massachusetts, have invented certain new and useful Improvements in Electric Bell-Pulls; and I do hereby declare that the following is a full, clear, and exact description of the same, reference being had to the annexed drawings, making a part of this specification, and to the letters and figures of reference marked thereon.

Figure 1 of the drawings is a side elevation of my invention, and Fig. 2 a longitudinal section thereof.

15 The present invention has relation to certain new and useful improvements in electric bell-pulls; and the object thereof is to simplify this class of devices, whereby they will be less liable to get out of order, will work more easily, 20 and may be manufactured and placed on the market at a comparatively small cost. These several objects I attain by the construction substantially as shown in the drawings and hereinafter described and claimed.

25 In the accompanying drawings, A represents the spindle, provided at its outer end with a suitable knob, a, or other equivalent device, for operating the spindle to pull it out in the direction of the arrows, Fig. 2. The 30 spindle A extends through a casing, B, cast with a circumferential flange, b, with holes through it to receive screws, by which it is attached to the jamb of the door or other object.

35 Located within the casing B, and coiled around the spindle A, is a spiral spring, c, retained in position on the spindle by a pin, d, passing through the same at a point beyond the inner end of the casing. Thus when the spindle is pulled out the spiral spring will be 40 contracted between the pin and outer end of the casing, and when the knob is released the expansive force of the spring will cause the spindle to return to its normal position. The inner end of the spindle A is screw-threaded 45 to receive and hold thereon a button, C, having its inner end conical or beveled, as shown at f. To more securely retain said button in position on the spindle, I employ a jam-nut, e, screwed on the extremity of the spindle until 50 it comes in contact with the end of the button, said nut being preferably round and of the

same diameter as the button. The button C is both removable and adjustable on the spindle A, to adapt it to a shorter or longer pull.

Around the inner end of the sleeve or casing B is placed and secured an insulator, D, and to this insulator are connected the ends of spring-arms E, of metal, and bent outward at an acute angle at their free ends, as shown at g, to conform to the bevel or conical surface of the button C, so that when the spindle A is pulled in an outward direction the bevel surface of the button will allow the angular ends of the spring-arms E to ride over it, and thus more perfectly make communication with the 65 conducting-wires F, to complete the circuit with the battery and cause the bell to ring. The employment of the casing B completely shields the spiral spring c, and prevents it from injury, as well as from the dust and dirt 70 that would work in between the coils thereof. The casing B has a further advantage, in that it can be cast with the escutcheon, or, in other words, the flanges b, rendering the device more simple, easily manufactured, and more 75 readily applied. The knob a is not made with a neck, as has been usually the case, in order to receive and connect thereto the end of a square-shaped spindle, and is consequently without any projections upon its inner side. 80 Hence space is economized between the escutcheon or flange and the knob, and the spindle being round instead of square, as is also the beveled button, the spindle can be readily turned upon its axis without affecting its operation, the button always being in position to 85 be brought in contact with the spring-arms when the spindle is pulled out. The interior or inner face of the knob a is made beveled, so that but a single point around the spindle will come in contact with the end of the casing, thereby leaving a sufficient space between the door-jamb and knob to enable the fingers to 90 grasp the latter in pulling the bell, thus dispensing with the usual neck or flange upon the inner side of the knob, and, as before stated, economizing space and enabling the device to be connected to door-jamb of less thickness.

Having now fully described my invention, 100 what I claim as new, and desire to secure by Letters Patent, is—

1. An electric bell-pull consisting of a casing cast with a circumferential flange, a spring and spindle constructed substantially as described, and an insulator adapted to fit over 5 the end of the casing, substantially as and for the purpose set forth.

2. In an electric bell-pull, the combination, with a suitable casing and an insulator fitting over the end of the same, of a spindle having 10 at one end detachably connected a beveled button, and at its opposite end a button formed with a conical or beveled inner face, substantially as and for the purpose set forth.

3. An electric bell-pull consisting of a casing cast with a circumferential flange or escutcheon, and having connected to its inner 15

end an insulator provided with curved or bent spring-arms and conducting-wires, and a spindle extending through the casing and insulator, and having a spiral spring coiled around 20 it, and provided at one end with a button formed with a conical or beveled face, and at the opposite end with a knob beveled outward upon its inner side from its center of axis, substantially as and for the purpose described. 25

In testimony that I claim the above I have hereunto subscribed my name in the presence of two witnesses.

AUGUSTUS S. BUNKER.
